UNITED STATES PATENT OFFICE.

ARTHUR CLAUSING, OF BERLIN-CHARLOTTENBURG, GERMANY, ASSIGNOR TO SIEMENS & HALSKE, AKTIENGESELLSCHAFT, OF SIEMENSSTADT, NEAR BERLIN, GERMANY, A CORPORATION OF GERMANY.

TELEGRAPH RECEIVING APPARATUS.

Application filed January 25, 1924. Serial No. 688,503.

To all whom it may concern:

Be it known that I, ARTHUR CLAUSING, residing at Berlin-Charlottenburg, Germany, have invented certain new and useful Improvements in Telegraph Receiving Apparatus, of which the following is a specification.

My invention relates to receiving apparatus for alternating and direct current telegraphy and kindred transmission of intelligence.

It is well known, that every system of telegraphy, irrespective of whether alternating or direct current be used at the transmitting station, works at the receiving apparatus with pulsating direct current

or, in the case of high-speed telegraphy with direct currents of positive and negative direction.

My invention is based upon the consideration that all these signalling currents possess an alternating current character and that in some respects it is not necessary to make a clear distinction between direct and alternating current telegraphy. Thus, for example, in telegraphy by means of positive and negative signal impulses of equal length, the so-called alternation, the alternating character of the current is at once obvious from the analytical expression therefore, which is:

$$i = I \frac{4}{\pi} \left(\sin \omega t + \frac{1}{3} \sin 3\omega t + \frac{1}{5} \sin 5\omega t + \dots \right) \quad (1)$$

For the telegraphy by means of signals of equal length ω depends upon the operating speed of the transmitting apparatus. If, for example, n be the number of signals per minute, it follows that

$$\omega = \frac{\pi}{12} n \quad (2)$$

From the equation 1 it will be seen, that the first harmonic ω participates in the rectangular curve form of the impulses with the whole, the third harmonic with one third and the fifth harmonic with one fifth of the amplitude.

In view of the fact that the first harmonic participates to the greatest extent in the formation of the rectangular curve forms and at the same time possesses the greatest amount of energy, I propose according to my invention to adapt the receiving apparatus, for example the telegraph relay for the first harmonic of the telegraph current, to the characteristic impedance of the line or to the impedance of the amplifier or rectifier tube to which the relay is connected.

In the above example the first harmonic is taken to be the value of ω computed from equation 2, as already stated. In the case of signal impulses and intervals of unequal lengths or durations the adaptation is effected to the signal impulse of the shortest duration. This holds good for alternating

current telegraphy, in which the signal impulse of the shortest duration is also chosen as the first harmonic.

If, for instance, a receiving relay be connected directly to a line of the characteristic impedance Z , the self-inductance of the relay must be made of such value that

$$Z = \omega L$$

The same equation also holds good for the rectifier in alternating current telegraphy. If the tube resistance be equal to Z , then the self-inductance L of the relay must be equal to

$$L = \frac{Z}{\omega}$$

in order that the relay coil may absorb a maximum of energy.

In many cases the receiving apparatus itself cannot be adapted to the tube without being given an abnormal shape. Thus, for instance, in telegraphy by means of equally long positive and negative signal impulses and 600 telegraph signals per minute

$$\omega = \frac{\pi}{12} n = 125$$

If a receiving relay is connected in series with a rectifier of say 30000 ohms internal resistance, then a rough calculation to ascer-

tain the necessary self-inductance of the receiving relay will give the result

$$L = \frac{Z}{\omega} = 200 \text{ henry.}$$

It is practically impossible to mount such an inductance upon an ordinary telegraph relay. Even when employing the thinnest wire only a small fraction of the calculated 10 henry value can be obtained in a relay of practical size.

According to my invention auxiliary means are in such cases employed to effect a suitable adaptation. In this connection the 15 application of translators primarily suggests itself as the simplest means of attaining the end in view. The translator is connected between the tube and the relay and for the first harmonic frequency ω adapted 20 on the one hand as closely as possible to the tube, and on the other hand to the relay.

My invention is illustrated in the accompanying drawing in which—

Figs. 1 and 2 represent diagrams of the 25 improved receiver circuits according to my invention.

Similar letters of reference indicate similar parts in the various figures of the drawing.

The relay is according to my invention 30 coupled with the anode circuit of a three electrode thermionic tube a by means of a translator U , as shown in Figs. 1 and 2, the translator being adapted as previously 35 described.

Experiments have proven that with receiver circuits according to my invention such large amounts of energy may be supplied to the relay, that at very great contact distances with small pole distance, up 40 to about 2000 telegraphy letters per minute can be transmitted. The anode current need only be a fraction of that which was required in the hitherto employed receiver 45 circuits. With a single small amplifier and rectifier tube a more reliable operation of the telegraph relay is attained, than with two amplifiers connected in parallel in the known receiver circuits, in which, furthermore, the relay is capable of operating only 50 when the distance between the contacts is as small as possible.

The preceding specification refers in particular to direct and alternating current 55 telegraphy over ordinary wire lines. It will, however, readily be understood that receiver circuits according to this invention may equally well be employed in connection with oscillatory circuits, receiving equipments for radio telegraphy and the like.

My invention is furthermore, by no means 60 confined to the use of translators as adaptors but any suitable method of adaptation may be used with equal advantage. If, for instance, filter chains are connected in the

receiver circuit their electrical values may be so chosen that they may likewise be employed for the adaptation of the receiving relay to the tube or the line.

What I claim as my invention and desire 70 to secure by Letters Patent is:—

1. A receiving system for alternating and direct current telegraphy having an impulse current of indefinite frequency, in which system the impedance of the receiving apparatus is made substantially equal to the impedance of the circuit element from which the receiving apparatus receives the current, the value of said impedances being determined by a frequency constituting the 75 succession of impulses of shortest duration in said impulse current of indefinite frequency for the purpose of transmitting the maximum amount of energy.

2. A receiving system carrying an impulse current of indefinite frequency and containing a thermionic tube in its circuit said tube being connected to the receiving apparatus, the impedance of said receiving apparatus being equal to the output impedance of said tube, the value of said impedance being determined by a frequency 80 constituting the succession of impulses of shortest duration in said impulse current of indefinite frequency, for the purpose of transmitting the maximum amount of energy.

3. A receiving system carrying an impulse current of indefinite frequency and containing a thermionic rectifier tube in its circuit, said tube being connected to the receiving apparatus, the impedance of said receiving apparatus being equal to the output impedance of said tube, the value of 90 said impedance being determined by a frequency constituting the succession of impulses of shortest duration in said impulse current of indefinite frequency, for the purpose of transmitting the maximum amount of energy.

4. A receiving system carrying an impulse current of indefinite frequency and being connected to a line, in combination with an intermediate element connected to said line and to the receiving apparatus, the input impedance of said intermediate element being equal to the surge impedance of said line and the output impedance of said intermediate element being equal to the impedance of said receiving apparatus, the value of said impedances being determined by a frequency constituting the succession of impulses of shortest duration in said 105 impulse current of indefinite frequency, for the purpose of transmitting the maximum amount of energy.

5. A receiving system carrying an impulse current of indefinite frequency and containing a thermionic tube in its circuit, in combination with an intermediate ele- 115

ment, connected to said tube and to the receiving apparatus, the input impedance of said intermediate element being equal to the output impedance of said tube and the output impedance of said intermediate element being equal to the impedance of said receiving apparatus, the value of said impedances being determined by a frequency cor-

responding to the frequency given by the succession of impulses of shortest duration 10 in said impulse current of indefinite frequency, for the purpose of transmitting the maximum amount of energy.

In testimony whereof I affix my signature.

ARTHUR CLAUSING.
